UNITED STATES PATENT OFFICE.

KANUTE A. ENLIND, OF SOUTH NYACK, NEW YORK.

AIRSHIP.

1,387,247.

Specification of Letters Patent. Patented Aug. 9, 1921.

Application filed July 23, 1919. Serial No. 312,691.

To all whom it may concern:

Be it known that I, KANUTE A. ENLIND, a citizen of the United States, and a resident of South Nyack, in the county of Rockland and State of New York, have made certain new and useful Improvements in Airships, of which the following is a specification.

My present invention relates generally to 10 airships and more particularly to that type of airships embodying rigid gas containers, my object being the provision of a construction applicable alike to large and small airships and of a nature which will afford 15 maximum protection and safety with speed and effectiveness especially as regards lateral stability.

In carrying out my invention, I propose an arrangement wherein rigid cylinders are 20 mounted in spaced parallel relation upon relatively opposite sides of a car, the latter of which may be of various structures and supported by the connections maintaining the cylinders in the relation stated, each of 25 these cylinders embodying a series of connected though separate gas containers, whose number and size may be varied to a great extent, rigidly connected to one another in the series and so disposed in relation to the 30 supports between the two cylinders as to avoid the necessity of encircling envelops and the like. These cylindrical gas containers may be substantially braced to prevent collapse and each cylinder, made up of 35 a series of containers, is preferably provided with outstanding horizontally disposed wings or fins which coöperate with the remaining general structure of the airship in prompting an exceedingly high degree of lateral stability.

In the accompanying drawings, illustrating my present invention:—

Figure 1, is a top plan view of my improved airship.

Fig. 2, is a vertical longitudinal section taken therethrough at substantially a central point.

Fig. 3, is an enlarged vertical transverse section through one of the cylindrical containers.

Fig. 4, is an end view.

Fig. 5 is a vertical transverse section through the longitudinal ridge beam.

Fig. 6 is a vertical section through the connecting shaft at a point between the containers.

Fig. 7 is a detail perspective view of certain of the connections as hereinafter described.

Referring now to these figures, my invention proposes a pair of longitudinal parallel cylinders which are disposed and connected in substantially the same horizontal plane and which are connected and braced in this relation by means of a series of horizontally disposed cross beams 10, as well as a plurality of inclined beams 11, the latter of which are connected at their opposing inner ends to the opposite sides of a central longitudinal ridge beam 12. This ridge beam 12, together with the inclined connecting beams 11, form a truss in respect to the transverse connecting bars or beams 10, the strut of which truss is constituted by the supports 13 of the navigating tower 14. This navigating tower is mounted on the supports 13, the latter of which are connected to ridge beam 12 and to certain lower horizontal cross beams 10, the latter of which support the car 15 in suspended relation therebeneath and between the lower portions of the spaced cylinders.

The foregoing relation of the parts is made possible without the necessity for supports of an enveloping nature, by virtue of the particular construction of the two cylinders, each of which is made up of a longitudinal series of cylindrical gas containers 16 whose ends are closed and connected in spaced apart relation by a hollow shaft 17 which passes axially through the several containers and is secured at its opposite ends to the conical end containers 18, the shape of which thus avoids excessive resistance to air. The several containers of each cylinder have independent intake and outlet openings normally closed by plugs 19 and the like as seen in Fig. 3, and are spaced apart at their ends in the direction of the length of the two cylinders, thus providing for the connection of the outer ends of the transverse connecting bars 10 and the inclined brace beams 11 to the hollow shaft 17 as seen in Figs. 6 and 7.

Each cylinder is made up of several containers as previously described, thus afford-

ing maximum protection to the car 15 suspended between their lower portions as well as to the navigating tower 14 projecting vertically between and beyond their upper portions. Each of the two cylinders is furthermore provided with a longitudinally extending and horizontally projecting wing or fin 20, rigid in connection therewith and outstanding therefrom, as particularly seen by comparison of Figs. 1, 3 and 4, so as to coöperate with the remaining structure and relation of the parts of the airship as previously described in forming an arrangement having great lateral stability and without materially reducing its ability as to speed and ready handling for which purpose the car 15 may have the forward and rear propellers 21 and 22 as well as a vertical rudder 23, the car itself containing any suitable motor for the operation of the former and controls for the latter.

By thus constructing each of the cylinders with a plurality of independent containers, it is obvious that accidental collapse, perforation, or other injury to one of the containers, need not necessarily result in disaster as in the case of the ordinary airship and in fact, it is contemplated that containers will be used in sufficient number in each cylinder to permit of the desired operation even should one or two of the containers be disabled for any reason.

It is obvious from the foregoing that my invention provides a remarkably stable arrangement and construction as applied to airships, as well as one of equal effective-

ness in connection with both large and small structures, to devices of the same nature.

I claim:

1. An airship comprising a pair of longitudinal parallel cylinders, each forming a series of independent cylindrical containers, a shaft extending axially through each of the cylinders and connecting the several containers thereof in endwise spaced apart relation and connections between the two cylinders including transverse horizontal connecting bars forming a car supporting frame and inclined brace beams, the outer ends of which are connected to said shaft between the containers, a longitudinal ridge beam to which the inner ends of the inclined brace beams are connected, and means connecting the ridge beam with the car supporting frame and forming with the ridge beam and brace beams a truss for the said frame. 40

2. An air ship comprising a pair of longitudinal, spaced cylinders, each having a longitudinal series of independent containers in endwise spaced relation, an axial shaft 60 extending through each of the cylinders and joining the several containers thereof, connections between the cylinders including transverse bars secured to the shafts of the cylinder, inclined brace beams, the outer ends of which are secured to said shafts, a ridge beam to which the inner ends of the brace beams are connected, a car suspended from the said transverse bars, and a navigating tower connected to said car and to 70 said ridge beam, as described. 65

KANUTE A. ENLIND:
